UNITED STATES PATENT OFFICE.

WILHELM HOHMANN, OF DELITZSCH, NEAR HALLE, GERMANY, ASSIGNOR TO ACTIEN GESELLSCHAFT FÜR ANILIN FABRIKATION, OF BERLIN, GERMANY.

APPARATUS FOR TREATING ARTIFICIAL THREADS WOUND ON BOBBINS.

Application filed December 1, 1924. Serial No. 753,252.

To all whom it may concern:

Be it known that I, WILHELM HOHMANN, a subject of the German Republic, residing at Delitzsch, near Halle, Germany, have invented certain new and useful Improvements in Apparatus for Treating Artificial Threads Wound on Bobbins, of which the following is a specification.

This invention relates to apparatus for 10 treating artificial threads wound on bobbins.

It is the principal object of the invention to provide an apparatus of the class referred to, based upon the effect of centrifugal force to pass a wash liquid through 15 threads wound on bobbins to obtain a thorough and rapid washing action.

A hollow spindle carries a perforated bobbin having advantageously a conical mouth to fit the spindle and a closed bottom so that 20 it requires no bobbin holder and twisting plate and is applicable to the spindles of any spinning machine. The spindle has perforations or slots so that as the centrifugal force due to the rotation of the bobbin 25 quickly expels liquid from the thread fresh washing liquid will be supplied by way of the spindle and its perforations. The liquid expelled by the centrifugal force is collected and drained away.

30 Other objects of the invention will appear from the specification in connection with the accompanying drawings in which an apparatus and its parts are schematically shown particularly adapted for the process described:

Fig. 1 shows in longitudinal section an arrangement in which an ordinary cylindrical bobbin having the usual fixing devices is used.

40 Figs. 2 and 3 show in longitudinal section and plan respectively a similar arrangement having a modified liquid supply.

Figs. 4 and 5 show similar arrangements in which cup-shaped bobbins are used.

45 Figs. 6 and 7 show different arrangements in longitudinal section for twisting the thread simultaneously with the washing operation.

50 Figs. 8 and 9 show different arrangements of perforations in the wall of the bobbin.

Fig. 10 shows in longitudinal section on

line A—B of Fig. 11 a machine for the treatment with liquid in which provision is made for recovering the vapor of the liquid.

Fig. 11 is a plan of Fig. 10 at the level F 55 on the one side and at the level J on the other side.

Fig. 12 is a transverse section of Fig. 10.

Fig. 13 may be a longitudinal section on line E—F of Fig. 15 of a machine for simultaneously twisting and reeling.

Fig. 14 shows a plan of the same machine.

Fig. 15 is a transverse section on line A—B of Fig. 14.

Fig. 16 is a transverse section on line 65 C—D of Fig. 13.

Fig. 1 shows a cylindrical bobbin having a perforated wall 2 (the perforations are shown only in the upper half of the wall) and carried and centered on the spindle 1 70 by means of a bell 3 and a plate 4. The free end of the spindle within the bobbin is hollow and has a number of perforations 6. Co-axial with the spindle and above it is the mouth of a pipe 5 from which liquid 75 may be discharged into the hollow spindle.

Figs. 2 and 3 show a similar bobbin mounted on a solid spindle 1. The liquid is discharged from an eccentrically arranged pipe 5 so that it flows at a flat angle on to 80 the plate 4 and enters the hollow bobbin through the openings 8 in the said plate.

In Fig. 4 the bobbin 9 is shaped like a cup and has a conical hub 11 by means of which it is fitted on the spindle 10. The upper edge 85 of the wall of the bobbin is curved inwards. The liquid is discharged into the bobbin through a co-axially placed pipe 5.

Owing to the centrifugal force the liquid is caused to rise up the wall of the bobbin 90 and to flow through the perforations in the wall thereof to pass through the thread wound upon the bobbin.

Fig. 5 shows a cup-shaped bobbin in a machine presently to be described. The 95 conical hub 12 of the bobbin 9 is drawn firmly against the flange of the rotating body 14 by means of a nut 13; the lower rim of this body is toothed and is supported by the ball bearing 15. The spray rim 16 prevents 100 the liquid from penetrating into the gear casing formed by the two plates 17. The

liquid is introduced through the pipe 5 into the bobbin and is distributed by the spray 18, whereby the weight of the rotating liquid is diminished as compared with the arrangement last described. A similar purpose is served by the openings 7 in the bell 3 of Fig. 1 which prevents the bobbin from becoming filled when the spindle happens to be at rest; the weight of discharge of liquid 10 would be liable to bend the spindle when the latter again rotates.

In Fig. 6 the construction of the spindle and bobbin corresponds with that shown in Fig. 1. The figure illustrates the twisting 15 of the thread simultaneously with the treatment with liquid. The nozzle 20 of the pipe 5 is arranged co-axially with the twisting eye 19 through which the liquid is discharged into the hollow spindle in a fine 20 stream and finds its way to the inner surface of the bobbin. Since the greatest strain on the thread during twisting is due to friction in the twisting eye the arrangement has the advantage that the strain is 25 diminished owing to the wetting of the thread by the liquid which is descending through the eye.

If, instead of the usual twisting eye there is used a funnel-shaped twisting eye 21 30 which is inwardly coned downwards (as shown in section in Fig. 7) fixed to a holder 22, a better guide is provided for the stream of liquid passing into the hollow spindle than is afforded by the usual twisting eye.

Figs. 8 and 9 illustrate the principle that the perforations in the wall of the bobbin should correspond with the thickness of the layer of thread wound on the bobbin in order that there should be a uniform action 35 of the liquid throughout the whole length of the winding. In the Fig. 8 the bobbin carries a barrel-shaped winding 23, the thickness of which diminishes uniformly towards the ends. Correspondingly the 40 perforations in the bobbin are so arranged that the distance between the perforations increases from the middle towards both ends and at these latter places the perforations 45 are of smaller diameter than those, 24, about the middle of the bobbin. In Fig. 9 the winding 26 is cylindrical but the winding has bevelled ends 27. In this case, therefore, the size of the perforations 28 is 50 substantially the same throughout except at the bevelled end of the winding where are 55 a series of perforations 29 of smaller area than that of those in the middle part. A machine for applying the centrifugal process is shown in Figs. 10-12. In the casing 60 60 are mounted a number of spindles 31, the driving pinions 32 of which are driven by gear wheels 33 common to all the spindle gears, and themselves driven by a pinion 34; the latter is connected by coupling 35 with 65 a shaft of motor 36. The casing contains

liquid supply pipes 37 which have the form of a ring, are controlled by valves 38 and can be turned about an axis in stuffing boxes 39. In this annular liquid supply pipe 37 there is a perforation corresponding with each hollow spindle and co-axial therewith. The liquid which has been expelled by centrifugal force collects in the bottom of the casing and runs away by pipe 40 into a drain or into a container, from which it 75 may be pumped back through pipe 37. The casing has a hinged lid 41 which is fastened by screw 42 during the operation of the machine. At one side of the casing there is an opening to a flue pipe 43 which removes 80 vapors evolved during the operation. This flue pipe which is controlled by a valve 44 may conduct the vapors removed by suction into a condensing or absorption system for their recovery. The whole of the spindle driving mechanism is contained in the casing 45 which is below the casing 30 and is mounted on legs 46.

The machine operates as follows:

The bobbins are mounted on the spindles 90 and the lid 41 is closed and fastened. The motor is then started and the valves 38 and 44 are opened. When the time necessary for the washing operation has elapsed the valves are closed again and the casing is 95 opened and charged with fresh bobbins.

A machine suitable for twisting the threads from the bobbins while they are subject to the treatment with liquid as indicated in connection with Figs. 6 and 7 is 100 shown in Figs. 13 to 16. The frame-work 47 carries a bar 48 on which the spindles 49 are mounted in a row, each being driven by a belt from a shaft 50. Above each bobbin 51 mounted on its spindle is a twisting eye 52 and above this a nozzle 53, as shown in Figs. 6 and 7. From this twisting eye the thread is led through a guide 54 and over the reel 55, of which there is a number mounted on a driving shaft 56. The liquid 105 flows through a pipe 57 under control of a valve 58 which is actuated in response to angular movement of the pipe about its axis into a pipe 60 which extends along the machine being supported in brackets 59 on 110 the frame. As indicated in Fig. 15 this pipe can be turned about its axis by handle 62; it has a number of branches 61 corresponding with the number of spindles. 115

This machine operates as follows:

By turning the handle 62 the several branch pipes 61 are brought into the position shown in dotted lines (Fig. 15) which movement also closes the passage 63 through the valve 58. The bobbins are now mounted on 120 the spindles and the threads laid around the drums. The pipe 60 is turned into the working position whereupon liquid flows through the open valve and is discharged through nozzles 53 and the twisting eyes into spindles 125 130

which have been set in rotation. The centrifuged liquid is received in the casing 64 from which it flows by pipe 65 to waste or to be pumped back through pipe 57.

5 The process as carried out with the apparatus described may be varied. For instance, the thread may be twisted from the bobbin as soon as the washing begins but in that case it is advantageous to provide a 10 subsequent washing on the reel, because the outer layers of thread which are the first to be twisted are liable to be unsufficiently washed.

15 In another mode of working the bobbin may first be rotated for a certain time, such as 10 minutes, warm water being allowed to flow through the spindle. Twisting and reeling then follow while the washing on the bobbin is continued in the manner already described. Finally, the procedure may be that 20 last described, the liquid into which the reel dips being, however, a desulphurizing bath. Another possible combination is to use a bleaching bath or dye bath.

25 What I claim is,—

1. Apparatus for treating artificial thread, comprising a hollow perforated cylinder defining a bobbin, a spindle, means for detachably securing the bobbin to the 30 spindle and for centering it thereon, means for rotating the spindle and means for feeding a liquid into the interior of the bobbin.

2. Apparatus according to claim 1, in which the means for centering the cylinder defines a closure at least at one end of the cylinder.

3. Apparatus according to claim 1, in which the means for centering the cylinder defines closures at both ends of the cylinder.

40 4. Apparatus according to claim 1, in which the perforations of the cylinder are so distributed that under the influence of centrifugal force liquid will pass to the exterior at different rates at different points along the cylinder.

45 5. Apparatus for treating artificial thread, comprising a spindle, a laterally perforated bobbin on the spindle, means for feeding liquid into the interior of the spindle and means in the path of the liquid for twisting the thread.

50 6. Apparatus for treating artificial thread, comprising a spindle, a laterally perforated bobbin on the spindle, means for rotating the spindle, a twisting eye, and means for feeding liquid into the interior of the bobbin including a nozzle directing the liquid through the twisting eye.

60 7. Apparatus for treating artificial thread, comprising in combination a spindle, a laterally perforated bobbin on the spindle, means for reeling the thread from the spindle, and means for feeding liquid to the interior of the spindle.

65 8. Apparatus for treating artificial thread,

comprising in combination a spindle, a laterally perforated bobbin on the spindle, means for reeling the thread from the spindle, means between the reeling device and the bobbin for twisting the thread and 70 means for feeding liquid to the interior of the bobbin, said feeding means being constructed and arranged to subject the thread on its way between the bobbin and the reeling device to the action of the liquid. 75

9. Apparatus for treating artificial thread, comprising in combination a spindle, a laterally perforated bobbin on the spindle, means for reeling the thread from the spindle, a twisting eye between the bobbin and the reeling device and means for feeding liquid to the interior of the bobbin including a nozzle directing a stream of the liquid through the eye. 80

10. A machine for treating artificial thread, comprising a plurality of spindles carrying laterally perforated bobbins, means for rotating the spindles and means for feeding liquid into the interior of the bobbins, including a supply pipe mounted for 85 angular movement toward and away from the bobbins.

11. A machine for treating artificial thread, comprising a plurality of spindles carrying laterally perforated bobbins, means for rotating the spindles and means for feeding liquid into the interior of the bobbins, including a supply pipe mounted for 90 angular movement about its axis and means responsive to the angular movement for controlling the flow of liquid to the bobbins. 95

12. A machine for treating artificial thread, comprising a plurality of laterally perforated bobbins, means for rotating the bobbins, a plurality of means for reeling the thread from the bobbins, twisting eyes between the bobbins and the reeling means and means for feeding liquid into the interior of the bobbins, including discharge pipes disposed to normally direct the liquid through the twisting eyes and movable as a unit out of said normal position. 100 105

13. A machine for treating artificial thread, comprising a plurality of laterally perforated bobbins, means for rotating the bobbins, a plurality of means for reeling the thread from the bobbins, twisting eyes between the bobbins and the reeling means and means for feeding liquid into the interior of the bobbins, including a supply pipe angularly movable about its axis and a plurality of discharge pipes terminating in nozzles normally disposed to direct the liquid through the twisting eyes. 115

14. Apparatus according to claim 12 including means responsive to the movement of the discharge pipes for controlling the flow of liquid to the bobbins. 120 125

15. Apparatus for treating thread, comprising a hollow perforated cylinder defin- 130

1 ing a bobbin, a vertical spindle for rotating the bobbin, and means for feeding liquid into the interior of the bobbin, including means for distributing the liquid over the interior surface of the bobbin.

5 rotation thereof.

16. Apparatus according to claim 15, wherein the spindle extends through the

bobbin and is hollow and provided with perforations whereby liquid fed into the hollow spindle during rotation thereof is distributed over the inner surface of the bobbin.

In testimony whereof I affix my signature.

WILHELM HOHMANN.
